UNITED STATES PATENT OFFICE.

HENRY G. VOIGHT, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR-CONTROLLING MEANS FOR ELEVATORS.

1,108,481.

Specification of Letters Patent. Patented Aug. 25, 1914.

Application filed May 8, 1913. Serial No. 766,247.

To all whom it may concern:

Be it known that I, HENRY G. VOIGHT, a citizen of the United States, residing at New Britain, Hartford county, State of Connecticut, have invented certain new and useful Improvements in Door-Controlling Means for Elevators, of which the following is a full, clear, and exact description.

The present invention relates to means for controlling the power which operates elevators and the like, which means may be operated by the movement of an elevator well door to condition the power means so that the elevator may not be moved until the particular door opposite which it happens to stand is fully closed or substantially so.

To this end and in a broad sense my invention consists in providing an arm movable with the opening and closing of the door and arranged to operate a power controlling electric switch. This switch may operate either to alternately make and break the motor circuit of an electric elevator or may operate electric means controlling the valve of a hydraulic elevator. The particular specific controlling means is immaterial as far as the purposes of the present invention are concerned.

In the following specification I am describing in detail a preferred embodiment of the invention, the preferred structure being illustrated in the accompanying drawings forming part of the specification.

In these drawings, Figure 1 is a fragmentary view in elevation of an elevator well door and casing, the parts being viewed from the interior or elevator side of the well. Fig. 2 is a view of the power controlling parts shown in Fig. 1 but on an enlarged scale and constituting a transverse vertical section on the line *a—a* of Fig. 1. Fig. 3 is a side elevation of the parts shown in Fig. 2 with said parts in the door closed position illustrated in Fig. 1. Fig. 4 is a view similar to Fig. 2 but with the parts in the position they occupy when the door is opened. Fig. 5 is a fragmentary and vertical sectional view on the line *b—b* of Fig. 2. Fig. 6 is a detail of the ratchet actuating dogs. Fig. 7 is a fragmentary sectional view on the line *c—c* of Fig. 2. Fig. 8 is a diagrammatic view of one form of controlling circuit which may be used in connection with the door controlling mechanism in an elevator.

In Fig. 1 I am illustrating a door controlling arrangement providing an arm which moves with the opening and closing of the door, which arm is utilized to operate a power controlling switch. The specific construction of the door controlling parts forms no part of the present invention, but is described in detail in my prior Patent No. 1,041,706, dated October 15th, 1912, and in my pending application Serial No. 748,350.

Referring to the drawings by numerals, 1 indicates the sliding door of an elevator well.

2 is the door casing and 3 the wall of the elevator well constituting an abutment stationary relatively to the sliding door. To this abutment is secured a plate 4 carrying adjacent its inner edge a bracket 5 having spaced arms 5^a between which is pivoted the end of a swinging arm 6 having formed integrally therewith and adjacent its end, a transverse arm 7. This arm 6 is preferably formed as an integral casting and is provided with a channel 8 in one face thereof and with elongated slots 9 therein at the base of said channel. The lower end of the transverse arm 7 is pivotally connected to the piston 10 of a power closer cylinder 11. 12 designates a flat bar having its end seated in the channeled face 8 of the arm 6 and 85 adjustably secured thereto by means of bolts 12^a, this bar 12 forming with the arm 6 one lever member of a toggle lever, the other member of which comprises the lever 13 pivotally connected at its rear end to the forward end of the bar 12 and having its forward end pivoted to the door 1 adjacent its forward edge, as at 14. 15 designates an operating handle pivotally carried by the forward edge of the door and co-operating with 95 a cam arm 16 which engages a pin 17 carried by the lever 13. For a detailed description of the specific structure and operation of this form of door controlling means, reference may be had to my prior patent 100 and pending application aforesaid. It will suffice for the purposes of the present invention to state that the toggle, when the door is in closed position, is straightened out with its component levers in horizontal alignment to afford a dead center lock and that when, with the door closed, the handle 15 is moved by the operator, its cam arm 16 swings the toggle levers upwardly, breaking their horizontal alignment and dead 105 110

center lock and moving the door to opened position against the force of the power cylinder, the arm 6 swinging upwardly with the opening of the door, and when the handle 15 is released, swinging downwardly as the force of the power cylinder through arm 7 returns the toggle levers and door to their original door closed positions.

I have utilized the swinging movement of the arm 6 to operate switch actuating mechanism, this operation being calculated to move the switch member a predetermined distance to make and brake the contact alternately. I have found by experience that the "make" and "break" of this switch should be quickly made in order to avoid "burning out" and I am, therefore, illustrating and describing the power controlling switch as of the "snap" type.

The rear end of arm 6 is pivotally mounted between the arms 5^a of the bracket 5 by means of a bolt 18 forming a rock shaft, to which bolt or rock shaft the end of this arm is secured by means of a set screw, the rock shaft being journaled in the arms 5^a of the bracket 5 and having its end extending through and being likewise journaled in spaced arms 19^a of a second bracket 19 in horizontal alinement with the first bracket 5, both of these brackets being secured to the plate 4. A rock arm 20 has one end seated on the rock shaft 18 between the spaced arms 19^a of bracket 19, this rock arm being rigidly secured to the rock shaft by means of a set screw shown. When the arm 6 moves up and down with the opening and closing of the door, the arm 20 will oscillate back and forth. This movement is utilized to operate the following switch actuating mechanism. A third bracket 21 is provided, suitably attached to the plate 4 and having an oscillating disk 22 pivotally carried by its arm, this disk having an offset at one edge provided with a recess 23 therein and forming two arms between which a pin 24 carried by rock arm 20 seats. This disk 22 serves as a lever member and carries adjacent its edges at diametrically opposite points, a set actuating pawls or pallets 25 and 26, the latter being of greater length than the former and having a ratchet actuating tooth 26^a in its rear edge. Below the bracket 21 in substantial alinement therewith is another bracket 27 likewise secured to the plate 4 and having spaced arms 29 between which are mounted shafts 30 and 34 in horizontal alinement. The shaft 30 carries affixed thereto a ratchet wheel 31 in the same vertical plane with the pawls 25 and 26, this ratchet wheel being so positioned as to be engaged by these driving pawls, as will be hereinafter seen. The shaft 30 also carries a toothed gear 32 engaging with and operating a gear 33 carried by the shaft 34. The shaft 34 beyond the outer arm 29 of the

bracket is enlarged as at 35 and extends outwardly to an electric switch 36 of the "snap" type, the wires extending from said switch to the elevator power being indicated at 37. The switch may be provided with any suitable supporting means as a bracket 38 which may be secured to the abutment 4. The switch 36 in the present instance may be of the type requiring two quarter turns to break and then make the circuit forming contact and the gears 32 and 33 in such event would be in the ratio of two to one, it being intended that a one-eighth turn of the gear 32 is effected through the opening movement of the door, and another one-eighth turn by the closing movement, thereby transmitting to the switch controlling shaft 35 two quarter turns.

I prefer to provide a friction brake for engagement with the periphery of the disk 22 and to this end extend a spring arm 28 from the upper edge of bracket arm 29 to abut against the periphery of this disk. Also a spring pawl 39 is provided, which pawl may be secured to the plate 4 and extends to and cooperates with the ratchet wheel 31. It is also preferable to provide in addition to the friction brake 28, stop means for limiting the reverse movement of the disk 22, and to this end a pin 21^a extends transversely from the bracket arm 21, and the periphery of the disk 22 has extended therefrom a pin 22^a arranged to engage and be stopped by the pin 21^a at the end of the normal reverse movement of disk 22.

The arrangement of the driving pawls 25 and 26 is such that they transmit to the ratchet wheel 31, with the forward and reverse oscillations of disk 22, successive rotary impulses of equal length and also in the same direction so that the power switch operating shaft 35 is given successive quarter-turn movements with the opening and closing of the door. It will be evident that when the door is opened, the rock arm 20, through its pin 24, will swing the disk 22 forwardly from the position shown in Fig. 3 to that shown in Fig. 4. This movement of the disk will move pawl 26 downwardly to give the ratchet wheel 31 a one-eighth revolution and will retract the pawl 25 from its initial position a distance equal to another one-eighth turn of the ratchet wheel, so that when the door closes, the arm 20 will reverse the direction of movement of disk 22, moving pawl 25 forwardly to turn the ratchet wheel 31 the required distance and retracting pawl 26 to position it for another forward movement, when the door is again opened. The arrangement of the disk 22 and the pawls 25 and 26 therefore affords successive movement to the power switch shaft 35 in the same direction and of such length as to snap the switch from the "on" to the "off" position and again from the

"off" to the "on" position with the successive openings and closings of the well door of the elevator shaft. The operation of the switch 36 will be arranged to render inoperative and operative the controlling means by which the elevator car is moved. It will be evident, therefore, that with door controlling means such as described herein, it would be impossible to start an elevator car 5 from a landing until the door of said landing has been fully closed or substantially closed, depending upon the ratio of movement of the rock arm 20 and gearing controlled thereby relatively to the power switch 10 operating shaft, which ratio may be varied to suit the requirements of the particular case.

In the foregoing specification I have described a specific form of door operating mechanism; also a specific form of switch operating mechanism controlled thereby. I desire it understood, however, that the particular type of operating mechanism is immaterial as far as the purposes of the present invention is concerned, it only being necessary to provide an arm which is moved with the opening and closing of the door. It will also be evident that while I have described and illustrated a particular and preferable 25 embodiment of the power switch controlling mechanism, various changes in structure and relative arrangement of parts are possible within the spirit of the invention and the scope of the appended claims.

In Fig. 8 of the drawings I have illustrated a circuit which may be used in connection with the door controlling mechanism described herein and used in an elevator shaft. In this figure *a* designates the rotary switches on the entrance doors to the elevator shaft; *b* a suitable grounding medium to which one side of one switch *a* is connected. *c* refers to the motor which operates the elevator car *d*, one side of this motor being connected to the controller *e* of the car, and the other side of the motor to the end of the series of switches *a* opposite to the end of the series which is grounded. It will be understood that these switches 50 are connected in series. The other side of the controller *e* connects with one terminal of the electric power source *f* such as a generator, the opposite side of this generator being grounded and being thereby connected 55 with the first and grounded side of the series of switches *a*. It will be evident from this that if any one of the rotary switches *a* has been turned to circuit open position, the circuit through the motor, generator and controller will be broken and the car cannot move. The switch *a* will be in circuit open position, of course, when its entrance door to the elevator shaft is open, so that as long 60 as an entrance door is open, the elevator car 65 cannot be moved.

What I claim is:

1. A device of the character described, comprising an elevator car, and an elevator well door arranged for reciprocating movement, an electric circuit controlling the movement of said elevator car, said circuit including a rotary electric switch including an operating shaft therefor arranged adjacent said door, a rock shaft adjacent said switch, an arm connected to said door and to said rock shaft and moving with the reciprocations of said door to oscillate said shaft in successive opposite directions, and connections between said rock shaft and said switch operating shaft arranged to continuously rotate the latter in the same direction and into alternate circuit breaking and making positions with the successive and oppositely directed door opening and closing movements of said rock shaft, to thereby prevent the movement of said elevator car while said door is open. 70

2. A device of the character described comprising an elevator car and an elevator well door arranged for reciprocating movement, an electric circuit controlling the movement of said elevator car and including a rotary electric switch arranged on the well casing adjacent the said door, an operating shaft for said switch, an arm connected to said door to swing with the opening and closing movement thereof, operative connections between said arm and said switch operating shaft arranged to continuously rotate the latter in the same direction with successive 100 and oppositely directed door opening and closing movements of said arm, said switch and said arm co-operating to break said controlling electric circuit when said door is open and to close said circuit when said door 105 is closed whereby said car may be operated.

3. A device of the character described comprising an elevator car and an elevator well door arranged for reciprocating movement, an electric circuit controlling the movement 110 of said elevator car and including a rotary electric switch arranged on the well casing adjacent the said door, an operating shaft for said switch, a pivoted arm operatively connected with said door and swinging with the opening and closing movements thereof, operative connections between said arm and said switch operating shaft, said arm being arranged to operate said connections to continuously rotate said shaft in the same direction and into successive circuit making and breaking positions with the successive and oppositely directed movements of said arm into door closed and door opened positions respectively whereby said elevator 120 car controlling circuit is conditioned for car operation when the door is closed and is conditioned to prevent car operation when the door is opened. 125

4. A device of the character described com- 130

prising an elevator car and an elevator well door mounted for reciprocating movement, an electric circuit for controlling the movement of said car, said circuit including a 5 rotary electric switch having circuit making and breaking positions operating in said respective positions to prevent and permit movement of the elevator car, said circuit being positioned adjacent said door and having an operating shaft, an arm connected to said door to move in opposite directions with the reciprocation of said door in opposite directions, and a pawl and ratchet connection between said arm and said switch operating shaft, said connections being arranged to continuously rotate said shaft in the same direction and to alternate circuit breaking and making positions with the successive and oppositely directed door opening 10 and closing movements of said arm.

6. A device of the character described comprising an elevator car and an elevator well door arranged for sliding reciprocating movement, an electric circuit for controlling the movement of said elevator car, said circuit including a rotary electric switch positioned adjacent said door, a rock shaft adjacent said door, an arm operatively connected to said shaft and to said door to swing with the opening and closing movements of said door and to thereby oscillate said shaft with the reciprocation of said door in opposite directions, an operating shaft for said switch, and pawl and ratchet connections between said operating shaft and said rock shaft, said connections being arranged to continuously rotate said operating shaft in the same direction and into alternate circuit breaking and making positions with the successive reciprocations of said arm in opposite directions, said switch being moved to circuit breaking position 15 upon door opening movement of said arm to thereby block the movement of said elevator car when said door is open.

7. A device of the character described comprising an elevator car and an elevator well door mounted for reciprocating movement, an electric circuit for controlling the movement of said car, said circuit including a rotary electric switch having circuit making and breaking positions operating in said respective positions to prevent and permit movement of the elevator car, a pivoted arm 20 connected with said door and swinging in opposite directions with the opening and closing of the door, and pawl and ratchet connections between said pivoted arm and said switch operating shaft arranged to con-

tinuously rotate said shaft in the same direction with the successive and oppositely directed door opening and closing movements of said arm.

8. A device of the character described comprising an elevator car and an elevator well door arranged for sliding reciprocating movement, an electric circuit for controlling the movement of said elevator car, said circuit including a rotary electric switch positioned adjacent said door, a rock shaft adjacent said door, an arm operatively connected to said shaft and to said door to swing with the opening and closing movements of said door and to thereby oscillate said shaft with the reciprocation of said door in opposite directions, an operating shaft for said switch, and pawl and ratchet connections between said operating shaft and said rock shaft, said connections being arranged to continuously rotate said operating shaft in the same direction and into alternate circuit breaking and making positions with the successive reciprocations of said arm in opposite directions, said switch being moved to circuit breaking position 25 upon door opening movement of said arm to thereby block the movement of said elevator car when said door is open.
